HYDRAULIC COUPLING

Isaac C. Popper, New York, N. Y., assignor, by
mesne assignments, to Automatic Turbine Drive
Company, Inc., Providence, R. I., a corporation
of New York

Application November 5, 1934, Serial No. 751,668

33 Claims. (Cl. 60—54)

My invention relates to an improvement in turbine drives, hydraulic clutches or fluid fly-wheels, and is an improvement on the inventions disclosed in my pending applications, Serial 5 No. 697,334, filed November 9, 1933, and Serial No. 713,388, filed February 28, 1934.

In many respects the present invention is similar to those referred to, but it includes certain refinements which will be hereinafter fully described and set forth in the claims. The purpose of these particular improvements is to gain a faster start, a quicker pick-up, and more power in climbing hills as well as in ordinary travel.

This invention like the others above-mentioned 15 includes two rotors having opposed counterpart cooperating buckets or scoops formed by spaced vanes or partitions of special and novel form, one of these rotors being secured to the fly-wheel and the other to a driven shaft, the buckets or scoops 20 and vanes or partitions being properly housed to form intercommunicating fluid chambers in combination with a reservoir which automatically keeps the pressure and the supply of fluid more or less constant.

With this combination of elements, a gearless 25 hydraulic turbine clutch and transmission are provided, which makes it possible for the operator to control the movement of the car by feeding gas when the car is started and driven, and applying the brake when the speed is to be reduced and/or the car is to be brought to a stop.

In the accompanying drawings:

Fig. 1 is a section through the various parts constituting my improved invention;

Fig. 2 is a face view of the driving rotor taken 30 on line 2—2 of Fig. 1;

Fig. 3 is a similar view of the driven rotor taken on line 3—3 of Fig. 1;

Fig. 4 is a perspective view of the driven shaft;

Fig. 5 is a fragmentary perspective of a portion 40 of the driving rotor;

Fig. 6 is a section on the line 6—6 of Fig. 1, looking in the direction of the arrows;

Fig. 7 is a greatly enlarged fragmentary sectional view through the two rotors showing diagrammatically the relative relationship between the two;

Fig. 8 is an enlarged section on the line 8—8 of Fig. 3 looking in the direction of the arrows;

Fig. 9 is a view of a modified form of rotor 50 which is similar to the other rotors except that the annular baffle is omitted entirely.

The numeral 1 represents the fly-wheel having the usual teeth 2 around its periphery for the 55 starter (not shown) to engage.

The numeral 3 indicates the driving rotor integrally or rigidly secured to the fly-wheel as viewed in Fig. 1.

The numeral 4 shows the driven rotor, and 5 is a casing held by bolts or other means 6 to 5 the fly-wheel 1, thereby enclosing the two rotors and forming a hydraulic chamber 7 between the casing and the flywheel, which thus constitute a housing for the hydraulic fluid.

The two rotors are provided with oppositely 10 facing vanes 8 and 9 respectively, the driving rotor 3 preferably having two more vanes than the driven rotor 4. Obviously this difference in number of vanes may be varied, as one rotor might have four more vanes than the other and possibly even more, according to circumstances. This provision is mainly designed to lessen any tendency to stall the motor in the transmission of power from one rotor to the other, and the principle is readily understood because the differential 15 in vanes insures against more than two vanes on each rotor ever being opposite the vanes on the other, so that at all times there is a constant flow and agitation in and out and freedom of movement of the fluid between the vanes of 20 the two rotors. The vanes 8 and 9 are spaced apart so as to form buckets or scoops 50 and 51, respectively, therebetween.

In the particular construction illustrated, the 25 vanes 8 in the driving rotor 3, and the vanes 9 in the driven rotor 4 are partially separated by annular, oppositely placed baffle-rings 52 and 53 respectively. As disclosed, these are flat on their outer faces and rounded on their inner faces. They are similar to corresponding baffles shown 30 in my previous applications, but much narrower. The contemplated purpose of these baffle-rings is to direct and insure the proper passage and circulation of the fluid. I have found by actual 35 experimentation and use that a faster start, a quicker pick-up, and more power, along with other features, results from this change in the dimensions of the baffle-rings, and I even contemplate dispensing with them altogether as illustrated in Fig. 9, in which the construction of 40 the vanes is the same as in Figs. 1 to 8, except that the baffle-rings are entirely omitted. Other important advantages reside in the particular 45 formation of the vanes or partitions which differ from those employed in my former applications, 50 as will now be pointed out.

Each of the vanes or partitions 8 and 9 has 55 its inner end portion, inside the ring 52 or 53, designated by the numeral 55, and the outer end portion, externally of the ring 52 or 53 55

designated 56. These end portions 55 and 56 are in radial alignment and in reality are continuations of each other, except that the baffle-rings 52 and 53 partially separate them in the form shown in Figs. 1 to 8. On one side of each vane 8 or 9, the corresponding side faces of end portions 55 and 56 are directly in alignment and form a straight line or plane, as shown in Figs. 2 and 3; but on the other side of each vane 8 or 9 the corresponding side faces of end portions 55 and 56 are at an obtuse angle to each other for a portion of the height of each, the edge portions of each vane 8 or 9 being widened out at opposite ends as very clearly illustrated in Figs. 2 and 3, so as to form a thicker edge than the under part of each vane, as shown in Figs. 7 and 8. The edges of the portions 55 and 56 are beveled as at 57 and 57', the bevel always extending from the straight or plane face side, as will be seen in Figs. 2 and 3 and also in Figs. 7 and 8. The face of each portion 56 opposite the bevel 57', is concave or curved, as shown in Fig. 7 while the face of each portion 55, opposite the bevel 57, is inclined so as to form a side which is generally concave.

The vanes are thus formed to give a scoop formation to the buckets 50 and 51, which will be best seen by referring to Figs. 7 and 8.

The starting and turning of the driving-rotor 30 is counter-clockwise, looking forward, as indicated by the arrow in Fig. 2, or clockwise, looking rearward, as in Fig. 9, and of course the driven rotor 4 when facing the rotor 3, as in Fig. 1, is driven in the same direction, and, when in full operation, at the same speed, as if they were a single unit.

The purpose of these scoop-shaped buckets is to increase the vortex movement of the fluid between the rotors in a spiral direction into and out of the buckets as indicated by the curved arrows in Figs. 7 and 8. This, with the other novel features, gives the faster start, quicker pick-up, and the added power in hill-climbing and normal travel of the machine in which the mechanism is installed.

It will be observed that the driven rotor has a slight play back and forth on the squared end 11 of the shaft 10, as shown in Fig. 1, clearance being provided for this purpose. The drawings show the two rotors separated to the fullest extent possible, and this is the relative position at slow speed, such as when the engine or automobile is started, but as they gain speed the driven rotor is free to move toward the driving rotor. A thrust-bearing 21' which may be held in place by the crankshaft forms an abutment at one end and prevents the rotors from touching each other, while movement in the opposite direction is limited by the driven shaft 10 and the end of packing box 25 formed in the casing 5, so that the peripheral portion of the driven rotor will be held out of contact with the casing. As hereinafter explained, the driven rotor moves along the shaft in accordance with the pressure variations of the hydraulic fluid created by operating conditions.

The driven shaft 10 extends through the center of the casing 5, and one end is preferably squared as at 11 (see Fig. 4) and fitted to a corresponding aperture 12 through the center of the hub 13 of the driven rotor 4, as viewed in Fig. 1, to insure their rotating together.

The driven shaft is bored longitudinally through the center, as at 14 (as shown in Fig. 1) for a portion of its length to form a fluid-chan-

nel, and the lateral ducts 15 and 16 extend radially therefrom, and the ducts 15 are shown in registry with ducts 17 in the hub 13 of the driven rotor. The ducts 16 are in reserve to take the place of the ducts 15 when adjustment is made to take up for wear.

Ducts 18 communicate with the circumferential channel 19 in the gland 20, and ducts 21 are in reserve to take the place of the ducts 18 when adjustment is made to take up the wear of the packing and packing-rings.

The packings are indicated by the numerals 22, 23 and 24 (see Fig. 1). The packing-box 25, packing-rings 26 and 27, the gland 20 and the follower 28, all surrounding and concentric with the driven shaft 10, house and protect and hold under compression the several packings, so that there is no possibility of escape of the oil or other liquid.

The follower 28 is held against the packing 24 by a stout spiral spring 29. This spring 29 is backed by a cage 30 secured to a part 31 of the frame of the machine.

The numeral 32 represents a compression cylinder and fluid reserve tank of a compensator, 25 and 33 is a piston tightly fitted thereto and having packing-rings 34 to prevent the escape of fluid. A pipe 35 extends out of the head 36 of this cylinder and is connected with the channel 19 formed in the gland 20.

A sturdy spiral spring 37 held between the head 36 of the cylinder and the back of the piston 33 forces the piston forward at all times, or to the left in Fig. 1. Oil or other fluid may be supplied through an opening 43 in the casing 35 or through the hole 39 in the head 36 of the cylinder, which hole is closed by the screw-plug 40.

The chamber 7 between the driving and driven rotors, and the space between the piston and the head 36 of the cylinder, are in constant communication by reason of the communication provided through the flexible pipe 35, the bore 14 of the driven shaft, and the ducts 15 or 16, and 17, and the ducts 18 or 21 and the circumferential channel 19 of the gland 20.

To facilitate movement of fluid from one side of the chamber 7 to the other, the orifices 17a are formed in the hub 13.

In filling this space with the liquid, the piston-rod 41 is forced back against the expandible pressure of the spring 37, the desired amount of fluid is poured through the opening 43 above described, and the opening is then closed by a screw-plug 45, or the system may be filled through the hole 39, if desired.

The opening 43 may be turned to the bottom for draining the fluid chamber 7, and the parts turned in the opposite position, namely at the top, when the chamber 7 is to be refilled. A refilling of chamber 7 is seldom necessary if some proper fluid is used which will not heat excessively or vaporize. In filling the fluid chamber 7, the piston 33 is first forced part way back against the action of spring 37. The fluid is then poured in until it reaches the top. The air-hole 46 may be opened by removing the plug 47 to facilitate pouring in the fluid. After this has been done, the piston 33 is forced still further back against the pressure of spring 37, but preferably not all the way. By the suction thus created, the level of the fluid in the chamber 7 is lowered, and more fluid is poured in the space thus created at the top of the chamber until it reaches its full capacity or a prescribed level.

The plugs 45 and 47 are then screwed into the openings 43 and 46 and the mechanism is ready for use.

As fuel is fed to the engine, the crankshaft thereof is rotated, driving the fly-wheel which at first with its rotor moves independently of the driven rotor 4, and as the fly-wheel gains momentum the rotary motion is communicated to the driven rotor just as fast as it will respond, and with a very quick pick-up, the driven rotor almost immediately commences to turn with the driving rotor, and thus the driven shaft is set in motion and the wheels of the vehicle are made to turn and propel the vehicle without the possibility of any sudden jerk as is incident to the shifting of gears in the ordinary geared car when carelessly or unskillfully manipulated. Anything of the sort is rendered impossible in the present mechanism, which is one of the marked advantages of this invention.

My improved hydraulic transmission thus has a driving and a driven rotor within a hydraulic casing, one rotor being keyed to and slidably mounted on the driven shaft, and the chamber formed by the casing being in free communication with a reservoir containing fluid under pressure, whereby fluctuations of pressure within the casing are compensated for by interchange of fluid with the reservoir, there being a continual interchange of fluid between the casing and the reservoir in accordance with changes in operating conditions. When the motor is started, the flywheel, to which the driving rotor is secured, revolves at idling speed, the chamber within the casing being full of operating fluid. As the driving rotor rotates, the fluid is agitated and thus creates a pressure which forces the driven rotor away from the driving rotor, the driven rotor moving outwardly until its hub contacts the end of the casing packing box.

As the speed of the driven rotor increases, the driven rotor rotates to turn the driven shaft, the agitation being greater if the pulling of the car is heavy, and the slippage or difference between the speeds of the driving and driven rotors increasing. As the driven rotor picks up speed, the agitation lessens and a free circulation of fluid takes place between the driving and the driven rotors, the slippage decreasing, with a resultant reduction in friction. The increased pressure of the operating fluid at the periphery and between the casing and the driven rotor produces an inward movement of the driven rotor towards the driving rotor, and a condition is finally reached where both rotors revolve substantially as a unit, with very little slippage and resultant friction, with the result that there is a decrease in heating of the fluid, which heating is greatest at starting when the fluid agitation and slippage are greatest, the minimum heating occurring when both rotors revolve together substantially as a unit; the small amount of heating is readily taken care of by the circulation of the fluid throughout the inside and outside fluid chambers.

During the starting operation, the fluid agitation and the resulting pressure forces some of the fluid back to the reservoir, the fluid chamber around the driven rotor and the openings through the hubs of the rotors facilitating the fluid movement. When the agitation decreases and the circulation between the rotors begins to be a smooth circulation with substantially no friction, due to the synchronized movement of the driving and driven rotors, the fluid in the reservoir is forced back into and between the rotors on account of

the pressure in the reservoir. There is thus a constant back and forth movement of the fluid, responding to changes in road conditions and the changing pull of the car, this being largely dependent on the grade of the road. The automatic movement of the driven rotor thus becomes a movement which corresponds to the amount of gas fed to the engine, and to the road conditions, and the changing road conditions are, therefore, compensated for by control of the throttle.

For reversing and neutral any approved mechanism (not shown) may be used. In fact the ordinary shift-gears may be left in the car, if desired, and kept in high all the time, except when used for reversing and neutral or in climbing extra steep grades.

I claim:

1. In a hydraulic power transmission, driving and driven rotors arranged in parallel relation and having cooperating radial vanes in opposing sides thereof, each of said vanes in transverse cross-section having a side thereof concave, and the opposite side approximately straight, the vanes on the driving rotor being arranged with said concave sides forward, and the vanes on the driven rotor having said concave sides rearward.

2. In a hydraulic power transmission, driving and driven rotors cooperating for the transmission of power, a driven shaft having the driven rotor mounted thereon to rotate said shaft, said driven rotor having limited free sliding movement lengthwise of said driven shaft and being movable away from the driving rotor by the agitation of fluid upon slow movement of the driving rotor and thereafter being movable toward the driving rotor upon a substantial increase in speed.

3. In a hydraulic power transmission, driving and driven rotors cooperating for the transmission of power, a driven shaft having the driven rotor mounted thereon to rotate said shaft, said driven rotor having limited free sliding movement lengthwise of said driven shaft away from the driving rotor upon slow rotation of the driving rotor and automatically slidably toward the driving rotor upon an increase in speed of said driving rotor.

4. In a hydraulic power transmission, the combination of driving and driven rotors arranged for rotation in parallel relation, and cooperating radial vanes arranged in opposing sides of the rotors and constructed and arranged for creating a vortex action on fluid between the rotors upon rotation of the driving rotor, each of said vanes having radially spaced edge portions thereof flanged laterally and having the flanged side thereof concave and the opposite side thereof plane.

5. Mechanism of the character described including two rotors contiguously mounted and having opposed turbine buckets directed and opening toward each other, one of these rotors being automatically movable only a limited distance toward and away from the other, with a space therebetween adapted to change to respond to the action of the rotors upon a fluid confined therebetween, a compression chamber externally of the rotors in communication with the space between the rotors and adapted to receive a portion of the fluid between the rotors, and means for exerting pressure at all times upon said fluid in the compression chamber.

6. Mechanism of the character described including two rotors contiguously mounted and having opposed turbine buckets directed and opening toward each other, one of these rotors

being automatically movable only a limited distance toward and away from the other, with a space therebetween adapted to change to respond to the action of the rotors upon a fluid confined therebetween, the buckets being formed by spaced vanes or partitions, one wall of each of which is straight and the opposite wall angular, said straight and angular walls being opposite each other in the buckets of the two rotors.

10. 7. Mechanism of the character described including two rotors contiguously mounted and having opposed turbine buckets directed and opening toward each other, one of these rotors being automatically movable only a limited distance toward and away from the other, with a space therebetween adapted to change to respond to the action of the rotors upon a fluid confined therebetween, the buckets being formed by spaced vanes or partitions, one wall of each of which is straight with a beveled inner edge and the opposite wall angular, said straight and angular walls being diametrically opposite each other in the buckets of the two rotors.

8. In a hydraulic power transmission, the combination of driving and driven rotors arranged for rotation in parallel relation, said rotors having cooperating radial vanes in the facing sides thereof, each of said vanes having flange-like edge portions, the flange-like portions being laterally offset from the main portion of said vane in the same direction at both inner and outer ends of each vane, the flange-like portions of the driving rotor vanes being offset in the opposite direction from the flange-like portions of the driven rotor vanes.

9. In a hydraulic power transmission, the combination of driving and driven rotors arranged for rotation in parallel relation, said rotors having cooperating radial vanes in the facing sides thereof for creating a vortex action on fluid between the rotors upon rotation of the driving rotor, each of said vanes having a plane side face extending radially of the rotor throughout the width of said face and having its opposite side face plane radially of the rotor throughout a portion of the width of the vane and the remainder of said opposite side face laterally offset from said last-mentioned side face with said offset portion concave at least at the outer end of the vane, said offset portion being shaped to form a longitudinal obtuse-angle radially of the rotor the direction of the lateral offset of the vanes of the driving rotor being opposite to the direction of lateral offset of the vanes of the driven rotor.

10. In a hydraulic power transmission, the combination of opposed driving and driven rotors arranged for rotation and having means forming a hydraulic coupling therebetween, a casing secured to the driving rotor and enclosing the driven rotor, a driven shaft slidably carrying the driven rotor and having a driving connection therewith, said driven rotor being mounted for bodily movement automatically away from the driving rotor by the agitation of fluid upon slow movement of the driving rotor, and means for limiting the sliding movement of the driven rotor to prevent engagement of the peripheral portion thereof with the casing.

11. In a hydraulic power transmission, the combination of opposed driving and driven rotors arranged for rotation and having fluid means forming a hydraulic coupling therebetween, a casing secured to the driving rotor and enclosing the driven rotor, a driven shaft carrying the driven rotor and having a driving connection

therewith, said driven rotor being freely slidable upon the driven shaft and bodily movable automatically away from the driving rotor by pressure of fluid upon slow movement of the driving rotor, and means for limiting said sliding movement of the driven rotor preventing engagement of the peripheral portion thereof with the casing, said driven rotor being free to move toward the driving rotor upon an appreciable increase in speed.

12. In a hydraulic power transmission, the combination of opposed driving and driven rotors mounted for rotation and having means for forming a hydraulic coupling therebetween, a housing means enclosing the rotors, a driven shaft carrying the driven rotor and having a driving connection therewith, one of said rotors being mounted for bodily movement away from the other rotor by the agitation of fluid upon slow movement of the driving rotor, and means for limiting the bodily movement of said movable rotor to prevent engagement of the movable rotor with the casing.

13. In a hydraulic power transmission, the combination of opposed driving and driven rotors arranged for rotation and having fluid means forming a hydraulic coupling therebetween, a casing secured to the driving rotor and enclosing the driven rotor, a driven shaft carrying the driven rotor and having a driving connection therewith, said driven rotor being slidable upon the driven shaft and bodily movable away from the driving rotor by fluid pressure upon slow movement of the driving rotor, means for limiting said sliding movement of the driven rotor to prevent engagement of the peripheral portion thereof with the casing, and said driven rotor being free to move toward the driving rotor upon an appreciable increase in speed, and thrust bearing means limiting sliding movement of the driven rotor toward the driving rotor to maintain a predetermined spacing therebetween.

14. Mechanism of the character described including a casing, two rotors mounted therein in parallel spaced relation and having opposed turbine buckets directed and opening toward each other to provide a rotor fluid chamber therebetween, one of these rotors being free to move a limited distance toward and away from the other to provide a fluid chamber between the movable rotor and the casing which communicates with the rotor fluid chamber at the periphery and at a low pressure area, a compression chamber externally of the rotors in communication with the space between the rotors and containing fluid and adapted to receive a portion of the fluid between the rotors, and means for exerting pressure at all times upon said fluid in the compression chamber.

15. Mechanism of the character described including a casing, two rotors mounted therein, in spaced parallel relation and having opposed turbine buckets directed and opening toward each other, one of these rotors being freely movable a limited distance toward and away from the other and providing a fluid chamber between the movable rotor and said casing, which fluid chamber communicates with the chamber between the two rotors at the periphery and at a low pressure area, the buckets being formed with spaced vanes or partitions, one wall of each of which is straight and the opposite wall angular, said straight and angular walls being opposite each other in the buckets of the two rotors.

16. The combination of a casing forming a fluid

5 housing, a driven shaft, and driving and driven rotors within the casing, said rotors having vanes forming intervening buckets having inlet and outlet portions for circulating fluid in a spiral path between the rotors, said vanes being flanged laterally at the edges thereof to constrict the flow area of said buckets at both the inlets and outlets thereof.

17. The combination of a casing forming a fluid 10 housing, a driven shaft, and driving and driven rotors within the casing, said rotors having vanes forming buckets for circulating fluid in a spiral path between the rotors, said vanes being flanged laterally to constrict the flow area of the fluid 15 at the adjacent rotary surfaces, one side wall of the buckets being inclined toward the other side wall.

18. The combination of a driven shaft, driving 20 and driven rotors concentric therewith and forming a fluid chamber therebetween, a casing for said rotors providing an external fluid chamber between said casing and said driven rotor, said external fluid chamber communicating with said rotor fluid chamber at the periphery and at a 25 low pressure area, said driven rotor being freely slideable on said driven shaft, whereby said driven rotor moves on said driven shaft in response to variations of fluid pressure in said chambers.

19. In a hydraulic power transmission, the combination of a driven shaft, a driving and a driven 30 rotor in spaced parallel relation, said rotors being spaced adjacent the shaft to provide a fluid inlet therebetween, said driven rotor being freely slideable on said driven shaft, and a fluid pressure reservoir in communication with said fluid 35 inlet.

20. The combination of a driven shaft, driving and driven rotors concentric therewith, said rotors having cooperating opposed radial vanes 40 forming a fluid chamber therebetween, a casing enclosing the rotors and forming a second fluid chamber between said casing and one rotor, the latter being freely slideable with respect to the other rotor, a fluid inlet to said rotor fluid chamber between said rotors, and ducts respectively 45 connecting said rotor chamber peripherally with said second fluid chamber and said second fluid chamber with said fluid inlet.

21. The combination of a driven shaft, driving 50 and driven rotors concentric therewith, said rotors having cooperating opposed radial vanes forming a fluid chamber therebetween, a casing enclosing the rotors and forming a second fluid chamber between said casing and one rotor, the latter being freely slideable with respect to the other rotor, a fluid inlet to said rotor fluid chamber between said rotors, a pressure fluid reservoir in free communication with said fluid inlet, and chamber peripherally with said second fluid chamber and second fluid chamber with said fluid 55 inlet.

22. The combination of a driven shaft, driving and driven rotors concentric therewith and forming a fluid chamber therebetween, the driven rotor having a hub by which it is mounted to turn 60 with the driven shaft, said hub being slideable on said driven shaft, a casing enclosing the rotors and forming an unobstructed external fluid chamber around the driven rotor, the external fluid 65 chamber being in free communication at both the hub and periphery with the fluid chamber between the rotors, said rotors being spaced apart adjacent the shaft to provide a fluid inlet, and means on either side of the hub and in its path 70 for limiting the movement of the driven rotor 75

on the driven shaft, and constituting the sole means of preventing the driven rotor from contact with the driving rotor and the casing, whereby the flow of fluid in the fluid chamber between said rotor and the casing is controlled. 5

23. In combination, a set of driving and driven rotors forming a fluid chamber therebetween, one of said rotors being mounted to be freely slideable with respect to the other rotor, a casing forming a fluid chamber between itself and said slideable 10 rotor, said second fluid chamber being in free circulatory communication with said first fluid chamber at the periphery thereof, and at a low pressure area, whereby said slideable rotor moves to and from the other rotor in accordance with a 15 change in the fluid pressure in the two chambers, and a fluid reservoir containing reserve fluid under pressure and communicating with said fluid chambers.

24. A rotor for turbine drives having a central 20 hub, and radial vanes extending from said hub and forming buckets, said vanes each having lateral flanges at the inlet and outlet portions of said buckets, said lateral flanges being positioned on the same side of said vanes. 25

25. A rotor for turbine drives having radial vanes forming intervening buckets, the vanes each having lateral flanges on the outer edges thereof, said flanges tapering or widening from a point intermediate the ends of said vanes to- 30 ward each end thereof.

26. In a hydraulic power transmission, a casing, driving and driven rotors cooperating for the transmission of power and forming a fluid chamber therebetween, a driven shaft having the 35 driven rotor mounted thereon to rotate said shaft, said driven rotor having limited free sliding movement lengthwise of said driven shaft to provide a fluid chamber between said driven rotor and said casing, which fluid chamber communicates with the rotor fluid chamber at the periphery and at a point of low pressure area, whereby said driven rotor moves toward the driving rotor upon an increase in speed of said driving rotor. 40

27. A rotor for turbine drives having a central hub and vanes radiating from said hub to form intervening buckets, said buckets having inlet and outlet portions, the vanes each having lateral flanges at the hub ends which widen as they 45 approach the hub. 50

28. A rotor for turbine drives having vanes forming intermediate buckets, said buckets having inlet and outlet portions, the vanes each having lateral flanges at the face edges thereof, gradually widening from a point near the hub 55 of the rotor toward the ends thereof, the widened flanges at the ends toward the hub of the rotor being beveled and inclined.

29. In a hydraulic power transmission, the 60 combination of a shaft, driving and driven rotors, one of which is operatively connected to said shaft, a casing at least partly enclosing said rotors and into which the shaft extends, packing for the portion of the casing around the shaft, 65 said shaft having a bore therein communicating with the interior of the casing, a gland surrounding the shaft and communicating with the bore, packing for the said gland around the shaft, and a thrust bearing interposed between the first 70 and second-mentioned packings to reduce the friction therebetween.

30. In a hydraulic power transmission, the combination of a shaft, driving and driven rotors, one of which is operatively connected to said 75

shaft, a casing at least partly enclosing said rotors and into which the shaft extends, packing for the portion of the casing around the shaft, said shaft having a bore therein communicating with the interior of the casing, a gland surrounding the shaft and communicating with the bore, packing for said gland on the side contiguous said casing, a thrust bearing interposed between the first and second-mentioned packing tending to reduce the friction therebetween, packing for the opposite side of the gland around the shaft, a follower for the last-mentioned packing, and resilient means acting on said follower.

31. A rotor having radial vanes forming buckets therebetween, and an integral annular ring at a point intermediate the ends of the vanes, the vanes having lateral flanges all extending in the same direction which gradually increase in width from the ring toward their outer ends.

32. The combination of a driven shaft, driving and driven rotors concentric therewith and forming a fluid chamber therebetween, means for enclosing the rotors and forming an external fluid chamber between said means and one of the rotors, said fluid chambers freely communicating, the rotors having opposed, cooperating, radial vanes which create a flow of fluid in the fluid chamber between the rotors and the external fluid chamber, means providing a fluid inlet to said chambers between said rotors adjacent the shaft, and a pressure reservoir having means therein for maintaining hydraulic fluid under pressure in constant communication with said fluid chambers through the said fluid inlet, whereby the fluid in said fluid chambers and said pressure reservoir constitutes a completely closed fluid system under pressure.

ternal fluid chamber, said rotors being spaced adjacent the shaft to provide a fluid inlet, and a pressure reservoir having means for maintaining hydraulic fluid under pressure in constant communication with said fluid chambers through the said fluid inlet, whereby the fluid in said fluid chambers and said pressure reservoir constitutes a completely closed fluid system under pressure.

33. The combination of a driven shaft, driving and driven rotors concentric therewith and forming a fluid chamber therebetween, means for enclosing the rotors and forming an external fluid chamber between said means and one of the rotors, said fluid chambers freely communicating, the rotors having opposed, cooperating, radial vanes which create a flow of fluid in the fluid chamber between the rotors and the external fluid chamber, means providing a fluid inlet to said chambers between said rotors adjacent the shaft, and a pressure reservoir having means therein for maintaining hydraulic fluid under pressure in constant communication with said fluid chambers through the said fluid inlet, whereby the fluid in said fluid chambers and said pressure reservoir constitutes a completely closed fluid system under pressure.

ISAAC C. POPPER.
